UNITED STATES PATENT OFFICE.

WILLIAM S. RENCH, OF SAN DIEGO, CALIFORNIA.

CARD HOLDER.

Application filed December 6, 1921. Serial No. 520,418.

To all whom it may concern:

Be it known that I, WILLIAM S. RENCH, a citizen of the United States, residing at San Diego, in the county of San Diego and State of California, have invented a certain new and useful Card Holder, of which the following is a specification.

My invention relates to price tag holders, and more particularly to devices for holding price tags to be attached to boxes or crates containing fruit, vegetables and the like to be displayed for sale; and some of the objects of my improvements are: To provide a price tag holder which shall hold the tag safely in any position without liability of its accidentally slipping or falling out of the holder, and to accomplish this without the use of clamps or special fastening means but by simply pushing the tag or card into the holder; facility of inserting the price tag; simplicity of construction of the holder, it being formed of a single piece of sheet metal; facility of removing the price tag preparatory to inserting another; comparatively low cost of manufacture; light weight; neatness and attractiveness of appearance; and to provide a holder from which the tag may be viewed at an angle.

With these and other objects in view as will appear hereinafter my invention consists of the certain new and novel features of construction, combination and arrangement of parts and portions as will be hereinafter described in detail and particularly set forth in the appended claims, reference being had to the accompanying drawings and to the characters of reference thereon which form a part of this application in which:

Figure 1 is a face view of my tag holder with the tag in position and showing by dotted lines the position of the tag when partially removed; Fig. 2 is an enlarged end elevational view of the holder, and Fig. 3 is an enlarged side elevational view thereof.

Similar characters of reference refer to similar parts and portions throughout the several views of the drawings.

My invention consists essentially of a rectangular plate 1 of sheet metal formed with legs 2 and 3 at the back and its four edges 4, 5, 6 and 7 turned to form an internal peripheral groove or pocket 8.

The plate 1 is preferably formed of a single sheet of tin plate or other sheet metal which has considerable springiness. The

sheet from which the device is formed is substantially rectangular, having extensions at each side which form the turned edges 4 and 7 at the ends of the holder. The ends of the sheet form the legs 2 and 3. Tracing the sheet in Fig. 2 beginning with leg 2 it is curved outward, folded to form turned edge 6, folded reverse to form pocket or groove 8, extends across at an incline to the horizontal, forming the plate or face 1, turned to form pocket 8, then folded reverse to form edge 5 and finally curved over and downwardly to form the leg 3. The curves at 5, 6 and 8, besides providing means for easy construction out of a single piece also provide for maximum resiliency or springiness so that the holder may be adapted for various thicknesses of supports between the legs 2 and 3 so that the metal will not permanently bend when the legs are spread.

Leg 3 is longer than leg 2, in order that the holder may be grasped by leg 2, leg 3 placed against the support, such as the side or ends of a box, and by pulling at leg 2, the holder may be easily slid onto the support.

The blank from which the holder is formed is punched out with lateral ears which are turned to form the edges 4 and 7 and the pocket 8 thereunder.

Thus a pocket is formed on all four sides of the holder so that the price tag or card 9 is securely held therein against spilling out when the holder is inverted or brushed in any way. The tag 9 is formed of such width that it will slide easily lengthwise between the walls of the longitudinal pocket and of such length that when in contact at one end against the end wall of pocket 8 the opposite end of the tag will just come short of the edge 7 and will spring down against the flat bottom of face 1.

The manner of inserting the price tag 9 is shown in Fig. 3 and the manner of removing it in Fig. 1, where the point of a pen knife 10 or the like is shown inserted under the corner of the tag to lift and start the edge of the tag over the edge 7 of the holder.

Although I have shown and described a particular construction, combination and arrangement of parts and portions I do not wish to be limited to this particular construction, combination and arrangement but desire to include in the scope of my invention the construction, combination and ar-

angement substantially as set forth in the appended claims.

It is obvious that with this construction there is provided a price tag holder which 5 will hold the tag securely and safely in any position against spilling out, and that this is accomplished without the necessity of providing clamps or other special fastening means but simply by pushing the tag into 10 the holder; that the price tag is easily inserted and easily removed; that the construction is very simple, being formed from a single sheet and easily stamped into form; and hence that it may be manufactured at 15 a low cost; that it is of light weight, neat and of attractive appearance; and that the tag when displayed in my holder may be comfortably viewed at an angle relative to the support. Furthermore, it is obvious 20 that this holder may be quickly and easily applied to a support such as a shelf, box or crate and the like.

Having thus described my invention what I claim as new and desire to secure by Letters Patent is:

1. A price tag holder, consisting of a single blank plate made of springy sheet metal with a pair of loop flanges in spaced

relation transversely across said plate, said loops bent down so that they are in spaced 30 relation from the main body and the extended ends curved inwardly and extending backwardly, the ends of the main body turned backwardly in the direction of said loop flanges forming flanges on the ends, 35 one of said end flanges being considerably lower than the flange at the other end to permit the insertion of the card.

2. A price tag holder, consisting of a single blank plate made of springy sheet 40 metal bent inwardly at all four of its sides forming a turned flange surrounding a rectangular area, the flanges on the longer sides being formed of loops and the ends extending backwardly folded against the main 45 flange portion, then bent inwardly and extending parallel with each other at their extended ends, the end flanges being single and one of them being considerably lower than the other to permit the insertion of a 50 card over the top of one of said end flanges.

In testimony whereof, I have hereunto set my hand at San Diego, California this 30th day of November, 1921.

WILLIAM S. RENCH.
